United States Patent Office

Des. 216,346
Patented Dec. 16, 1969

216,346

WRITING INSTRUMENT DESK SET BASE

Nolan K. Rhoades, Beloit, Wis., assignor to The Parker Pen Company, Janesville, Wis., a corporation of Wisconsin

Filed Mar. 13, 1969, Ser. No. 16,229

Term of patent 14 years

Int. Cl. D19—02
U.S. Cl. D74—5

I claim:

The ornamental design for a writing instrument desk set base, substantially as shown.
